(57) **CLAIM**

The ornamental design for a collapsible nursing nipple, substantially as shown and described.

DESCRIPTION

FIG. 1 is a perspective view of a collapsible nursing nipple, shown in a collapsed configuration;

FIG. 2 is a perspective view of the collapsible nursing nipple of FIG. 1, shown exploded with the nipple collapsed for clarity of disclosure;

FIG. 3 is a top plan view of the collapsible nursing nipple of FIG. 1;

FIG. 4 is a cross-sectional elevation view thereof, taken along line 4-4 of FIG. 3;

FIG. 5 is a perspective view of the collapsible nursing nipple of FIG. 1, shown exploded with the nipple extended for clarity of disclosure;

FIG. 6 is a top plan view thereof; and,

FIG. 7 is a cross-sectional elevation view thereof, taken along line 7-7 of FIG. 6.

1 Claim, 7 Drawing Sheets
